US0D1040553S

(12) **United States Design Patent** (10) **Patent No.:** **US D1,040,553 S**
(45) **Date of Patent:** ** *Sep. 3, 2024

(54) **DISPENSER**

(71) Applicant: **Xela Innovations, LLC**, Glendale, WI (US)

(72) Inventor: **Todd J. Muderlak**, Whitefish Bay, WI (US)

(73) Assignee: **XELA INNOVATIONS, LLC**, Glendale, WI (US)

(*) Notice: This patent is subject to a terminal disclaimer.

(**) Term: **15 Years**

(21) Appl. No.: **29/815,556**

(22) Filed: **Nov. 15, 2021**

(51) **LOC (14) Cl. 12-15**

(52) **U.S. Cl.**

USPC **D23/355**

(58) **Field of Classification Search**

USPC D23/355, 356, 358, 359, 360, 364, 365, D23/366, 367

CPC . A61L 9/03; A61L 9/012; A61L 9/015; A61L 9/037

(57) **CLAIM**

The ornamental design for a dispenser, as shown and described.

DESCRIPTION

FIG. 1 is a front perspective view of the dispenser; FIG. 2 is a front elevational view of the dispenser; FIG. 3 is a rear elevational view of the dispenser; FIG. 4 is a bottom view of the dispenser; FIG. 5 is a top view of the dispenser; and, FIG. 6 is a right side elevational view of the dispenser; the left side being a mirror image thereof. The features shown in broken lines in FIGS. 1-6 illustrate environmental features that form no part of the claimed design.

1 Claim, 6 Drawing Sheets
